ATTORNEY.

UNITED STATES PATENT OFFICE.

CHARLES LEIB, OF PHILADELPHIA, PENNSYLVANIA.

DESIGN FOR A HOOK FOR GARMENTS.

SPECIFICATION forming part of Design No. 35,657, dated February 4, 1902.

Application filed December 21, 1900. Serial No. 40,696. Term of patent 14 years.

To all whom it may concern:

Be it known that I, CHARLES LEIB, a citizen of the United States, residing at Philadelphia, in the county of Philadelphia and State 5 of Pennsylvania, have invented and produced a new and original Design for a Hook for Garments, of which the following is a specification, reference being had to the drawings forming part thereof.

10 In the drawings, Figure 1 is a plan view of a hook constructed in accordance with my design. Fig. 2 is a side view.

The leading or material feature of my design consists of the rear looped ends of the hook, which from a point back of the bill diverge from each other rearwardly and outwardly, one of the said diverging ends consisting of two strands of wire, while the other diverging end consists of a single strand of 20 wire, each of the diverging ends being in the shape approximately of an arc of a circle.

The drawings show the hook as consisting of the shank, two of the strands 4 and 5 of which merge into the double-strand curved 25 diverging end 11, while the other strand 1 of which merges into the single-strand curved diverging end 2. The strands 1 and 5 of the

shank are at the front of the hook bent upwardly and backwardly to form the bill 8 and outwardly near the front of the hook to form 30 the enlargements 9, forming the openings 10. The front of strand 4 is bent upwardly and downwardly to form the swell or hump 7. The strands of the curved diverging end 11 are opened where they merge together at the rear 35 to form the loop 6, and the curved diverging end 2 is bent at its rear end to form the loop 3. The pronounced diverging curved form given to the looped ends 11 and 2 and the formation of one looped end of a single strand 40 and of the other loop of a double strand impart a distinctive as well as an ornamental appearance to the hook.

Having described my invention, what I claim as new, and desire to secure by Letters 45 Patent, is—

The design for a hook for garments as herein shown and described.

In testimony whereof I affix my signature in presence of two witnesses.

CHARLES LEIB.
